UNITED STATES PATENT OFFICE.

WALTER J. RICHARDS, OF MILWAUKEE, WISCONSIN, ASSIGNOR TO NATIONAL ELECTRIC COMPANY, OF MILWAUKEE, WISCONSIN, A CORPORATION OF WISCONSIN.

ELECTRICAL CONDUCTOR FOR DYNAMOS.

No. 905,230.

Specification of Letters Patent.

Patented Dec. 1, 1908

Application filed August 18, 1904. Serial No. 220,758.

To all whom it may concern:

Be it known that I, WALTER J. RICHARDS, citizen of the United States, residing at Milwaukee, in the county of Milwaukee and State of Wisconsin, have invented a certain new and useful Improvement in Electrical Conductors for Dynamos, of which the following is a full, clear, concise, and exact description, reference being had to the accompanying drawings, forming a part of this specification.

My invention relates to dynamo electric machines and has for its object more improved and more efficient means for securing a rigid and reliable electrical contact between the carbon brushes and the respective conductors which lead to the binding posts.

More particularly my invention provides means whereby an electrical contact of high conductivity is secured, and in addition, a mechanical appliance which insures a firm connection between the brush and pigtails.

This description will be more readily understood by reference to the accompanying drawings, in which:

Figure 1 is a front view of the brush and pigtails, and Fig. 2 is a section on the line 2--2 of Fig. 1.

30 The brush 10 is provided with the copper coating 11. This copper coating may be secured by the process of electro plating. A rivet 12 is inserted in the brush 10, an end 14 thereof extending outside of the carbon.

35 The pigtails 13 may be soldered to the copper plate and also soldered or otherwise fastened to the end 14 of the rivet 12, which extends through a flattened end or terminal 15 of the pigtails 13. The soldering of the 40 pigtails to the copper coating of the carbon brush insures electrical conductivity, while the soldering or otherwise fastening of the pigtails to the copper rivet insures a rigid connection. Thus a contact between the 45 brush and pigtails is secured which is mechanically rigid and electrically reliable, without adding unnecessary weight to the device.

While I have herein shown and described a preferred embodiment of my invention, it will be understood by those skilled in the art that modifications and changes may be made without departing from the spirit thereof. I do not wish, therefore, to limit myself to the precise construction herein set forth, but

Having described my invention, I claim as new and desire to secure by Letters Patent:

1. The combination of an electroplated carbon brush, a flexible pigtail for transmitting current to or from said brush, a rivet for mechanically connecting said pigtails to said brush, said rivet being soldered to the pigtails, said rivet providing a path of high electrical conductivity between said pigtails and the metallic coating of said brush.

2. In combination, a carbon dynamo brush, a metallic plating thereon, a flexible pigtails conductor soldered to the metallic coating of said brush, and a rivet soldered to said pigtails serving mechanically to attach said conductor to said brush.

3. The combination of a carbon brush, a flexible pigtails for transmitting current to or from said brush, said pigtails having a flattened end, a rivet soldered to said flexible pigtails, thus making a rigid connection between said flattened end and the upper end of the brush, and a coating on the brush providing a path of high electrical conductivity between said pigtails end and brush.

4. The combination of a carbon brush, a flexible pigtails for transmitting current to or from said brush, said pigtails having a flattened end, a rivet passing through said flat end and the end of said brush for mechanically holding said pigtails in engagement with said brush, said pigtails being soldered to said rivet, and a coating on said brush providing a path of high electrical conductivity between said pigtails end and brush.

5. The combination of a carbon brush, a metallic coating thereon and in intimate contact therewith, a flexible pigtails for transmitting current to or from said brush, said

pigtail having a flattened end, a rivet passing through said flat end and soldered thereto, said rivet also passing through the upper end of said brush for holding said pigtail in firm engagement with said brush, said pigtail end being also soldered to said metallic coating.

In witness whereof, I hereunto subscribe my name this 8th day of August A. D., 1904.

WALTER J. RICHARDS.
